SAFETY CLIP

Homer D. Miller, Canton, Ohio

Application March 18, 1946, Serial No. 655,210

8 Claims. (Cl. 24—11)

1

The invention relates to safety clips for fountain pens, pencils and similar articles which are ordinarily carried in a pocket of the user, and more particularly to a simple, inexpensive and efficient safety device which may be applied to the ordinary type of clip used for such articles.

It is an object of the invention to provide a safety clip for fountain pens and the like comprising a spring clip of conventional form having a reversely disposed pin or spur thereon adapted to engage in the material of the pocket in which the pen is placed for securely retaining the pen within the pocket and prevent accidental displacement thereof.

Another object is to provide a safety clip of this character in which a manually operable tubular member is slidably mounted upon the pin or spur for releasing the pen from the fabric and covering the point thereof to permit removal of the pen from the pocket.

A further object is to provide a devise of the character referred to in which the sliding tubular member which operates the pin or spur is of generally spherical contour.

A still further object is to provide such a safety clip in which the sliding tubular member is carried by a finger piece slidably mounted upon the clip proper.

Another object of the invention is to provide a safety clip of this character in which the sliding tubular member which controls the pin or spur is operated by a lever pivoted upon the clip.

The above objects, together with others which will be apparent from the drawing and following description, or which may be later referred to, may be attained by constructing the improved safety clip in the manner hereinafter described in detail and illustrated in the accompanying drawing, in which:

Figure 1 is a side elevation of a fountain pen provided with the improved safety clip showing the sliding tubular member in position to cover the point of the pin or spur to permit removal of the pen from a pocket;

Fig. 2 a similar view showing the sliding tubular member in position to permit the pin or spur to engage the material of a pocket in which the pen is located;

Fig. 3 an enlarged fragmentary elevation of the clip, with parts broken away, showing the manner in which the pin or spur engages the material of the pocket when the pen is located therein;

Fig. 4 a transverse sectional view through the clip showing the manner in which the tubular

2

sliding member upon the pen is carried by the finger piece slidably mounted upon the clip;

Fig. 5 an enlarged fragmentary sectional view of the lower portion of the clip showing a slightly modified form of sliding tubular member and finger piece;

Fig. 6 a transverse sectional view through the clip shown in Fig. 5;

Fig. 7 a fragmentary elevation with parts broken in section, of the lower portion of the clip illustrating a modified form with lever operated means for operating the tubular sliding member, showing the parts in position to permit the pin to engage the material of a pocket, and;

Fig. 8 a similar view showing the lever operated to position to withdraw the point of the pin or spur from the material and enclose the same within the sliding tubular member.

Referring first more particularly to the construction shown in Figs. 1 to 4 inclusive, a fountain pen is indicated generally at 10 provided with the usual removable cap 11 to which is connected the clip indicated generally at 12 which may be of conventional construction.

The clip 12 may be formed of spring metal of slightly arcuate form, the upper end thereof being connected to the cap 11 of the pen in any usual and well known manner as indicated at 13 and a ball 14 being formed at the lower free end of the clip and adapted to normally engage the side of the cap 11 in usual and well known manner, so as to tend to pinch a portion of the material of the pocket between the ball 14 and the cap 11 when the pen is placed in the pocket by the user.

Even though a considerable tension is maintained upon this ball it is found in practice that it frequently happens that pens, pencils or the like provided with such clips will accidentally become dislodged from the pocket resulting in loss or damage to the pen or pencil.

The present invention contemplates a simple, efficient and easily operated safety attachment which may be applied to the conventional clip illustrated and above described, which will positively secure the pen, pencil or other article in the pocket and prevent accidental removal therefrom.

To this end a reversely disposed, angularly located pin or spur 15 is formed integrally with, or rigidly secured to, the clip 12, the base portion 16 of this pin being preferably connected to the ball 14 of the clip while the pointed end 17 thereof is angularly disposed toward the pen or pencil so as to engage in the material of the pocket when the pen or pencil is placed therein.

For the purpose of operating the pin or spur 15 to withdraw it from the operative position shown in Figs. 2 and 3, to the inoperative position shown in Fig. 1, a tubular member 18 is slidably mounted upon the pin or spur 15 and adapted to be normally positioned in the lower position shown in Figs. 2 and 3 permitting the pin to be located at an angle toward the pen, so as to engage the material M of the pocket, and to be manually raised to the upper position shown in Fig. 1 to pull the pin into position substantially parallel to the pen and enclose the pointed end 17 thereof as shown in Fig. 1.

The sliding member 18 is preferably of generally spherical shape as shown in Figs. 1 to 4 inclusive, as this shape will readily facilitate pushing the material off of the pointed end of the pin when it is desired to remove the pen from the pocket.

The tubular sliding member 18 may be operated by the finger piece indicated generally at 19 which is slidably mounted upon the clip 12. For this purpose an elongated slot 20 is provided in the clip 12 and a bar 21 connecting the finger piece 19 to the tubular member 18 is located through said slot.

Flanges 22 may be formed on the side edges of the finger piece 19 and located over the side edges of the clip 12 and the outer faces of the finger piece 19 may be serrated as at 23 so as to be frictionally engaged by the finger for sliding this finger piece upon the clip 12 from the position shown in Figs. 2 and 3 to that shown in Fig. 1.

A slight modification of the invention is shown in Figs. 5 and 6 in which the clip 12a may be the same construction as above described having the ball 14a at its lower end and the pin or spur 15a formed integrally with or connected thereto in the manner above described.

The finger piece 19a may be formed of sheet metal and bent to tubular, rectangular cross sectional shape as shown in Fig. 6 so as to slidably mount the same upon the clip 12a and the integral flange 21a may be formed thereon having its end formed into a tube 18a slidably mounted upon the pin 15a.

The upper end of the tube 18a is preferably rolled as indicated at 18' in order to more easily push the material of the pocket from the point of the pin when it is desired to remove the pen from the pocket.

In order to limit the movement of the sliding finger piece 19a upon the clip 12a in each direction, any suitable form of projection or shoulders 24 may be formed and properly spaced upon the clip, acting as stops to limit the movement of the finger piece.

The operation of the form of the invention shown in Figs. 5 and 6 is the same as that described in detail pertaining to Figs. 1 to 4 inclusive.

As shown in Figs. 7 and 8 the tubular sliding member which controls the pin or spur may be operated by lever means instead of by the sliding finger piece above described. In this case the clip 12b may be of the same conventional design as above, with the ball 14b at its lower end and the pin or spur 15b fixed thereto.

The sliding tubular member 18b may be operated by means of a bell crank lever 25, fulcrumed intermediate its ends within the slot 26 in the clip, as by the pivot pin 27, one arm 28 of the bell crank lever being pivotally connected as at 29 to the sliding tubular member 18b, the other arm 30 of the bell crank lever being located

upon the outer side of the clip and adapted to be manually operated.

In normal position the lever arm 30 lies against the outer side of the clip as shown in Fig. 7, the sliding tubular member 18b being located around the pin 15b at a point spaced from the point 17b thereof so that the point of the pin will engage in the material of the pocket when the pen is placed therein.

10 In order to remove the pen from the pocket, the lever arm 30 is swung outward and downward to the position shown in Fig. 8 and through the arm 28 the sliding tubular member 18b is moved upward upon the pin pushing the material of the pocket therefrom and enclosing the point 17b of the pin within the tubular member 18b as shown in Fig. 8 so that the pen may be withdrawn from the pocket.

15 It will be obvious that since the normal position of the pin or spur is at an angle to the clip, as shown in Figs. 2, 3 and 7, the pin will be under tension when the tubular sliding member is moved to the position shown in Figs. 1, 5 and 8, and this tension upon the pin is sufficient to throw the tubular member back to the normal position as soon as the finger piece is released, whereby the pin will always be in position to engage the material of the pocket except when the finger piece is manually operated.

20 I claim:

1. In combination with a fountain pen and the like, a clip fixed at one end to the pen and having its other end located adjacent to the side of the pen, a reversely disposed, angular pin connected to the last named end of the clip and normally disposed toward the pen, a tubular member slidably mounted upon the pin and means for sliding the tubular member upon the pin to enclose the end of the pin therein.

2. In combination with a fountain pen and the like, a clip fixed at one end to the pen and having its other end located adjacent to the side of the pen, a reversely disposed, angular pin connected to the last named end of the clip and normally disposed toward the pen, a tubular member slidably mounted upon the pin and means for sliding the tubular member upon the pin to enclose the end of the pin away from the pen.

3. In combination with a fountain pen and the like, a clip fixed at one end to the pen and having its other end located adjacent to the side of the pen, a reversely disposed, angular pin connected to the last named end of the clip and normally disposed toward the pen, a tubular member slidably mounted upon the pin and a finger piece slidably mounted upon the clip for sliding the tubular member upon the pin to enclose the end of the pin therein.

4. In combination with a fountain pen and the like, a clip fixed at one end to the pen and having its other end located adjacent to the side of the pen, a reversely disposed, angular pin connected to the last named end of the clip and normally disposed toward the pen, a substantially spherical tubular member slidably mounted upon the pin and means for sliding the tubular member upon the pin to enclose the end of the pin therein.

5. In combination with a fountain pen and the like, a clip fixed at one end to the pen and having its other end located adjacent to the side of the pen, a reversely disposed, angular pin connected to the last named end of the clip and normally disposed toward the pen, a tubular member slidably mounted upon the pin and a finger piece

slidably mounted upon the clip, there being a slot in the clip, and a bar located through said slot and connecting the finger piece to the tubular member, for sliding the tubular member upon the pin to enclose the end of the pin therein.

6. In combination with a fountain pen and the like, a clip fixed at one end to the pen and having its other end located adjacent to the side of the pen, a reversely disposed, angular pin connected to the last named end of the clip and normally disposed toward the pen, a tubular member slidably mounted upon the pin and a finger piece of tubular cross section slidably mounted around the clip, and a flange upon the finger piece connected to the tubular member for sliding the tubular member upon the pin to enclose the end of the pin therein.

7. In combination with a fountain pen and the like, a clip fixed at one end to the pen and having

its other end located adjacent to the side of the pen, a reversely disposed, angular pin connected to the last named end of the clip and normally disposed toward the pen, a tubular member slidably mounted upon the pin and a lever upon the clip for sliding the tubular member upon the pin to enclose the end of the pin therein.

8. In combination with a fountain pen and the like, a clip fixed at one end to the pen and having its other end located adjacent to the side of the pen, a reversely disposed, angular pin connected to the last named end of the clip and normally disposed toward the pen, a tubular member slidably mounted upon the pin and a bell crank lever pivoted upon the clip and pivotally connected to the tubular member for sliding the tubular member upon the pin to enclose the end of the pin therein.
